UNITED STATES PATENT OFFICE.

CARGILL BLOW, OF WINTER HAVEN, FLORIDA.

DESIGN FOR A DOORSTOP.

Application filed March 19, 1928. Serial No. 25,900. Term of patent 3½ years.

To all whom it may concern:

Be it known that I, CARGILL BLOW, a citizen of the United States, residing at Winter Haven, in the county of Polk and State of Florida, have invented a new, original, and ornamental Design for a Doorstop, of which the following is a specification, reference being had to the accompanying drawing, forming part thereof.

Fig. 1 is a front view of a door-stop, showing my new design, and Figure 2 is a side view of said door-stop.

I claim:

The ornamental design for a doorstop, as shown.

CARGILL BLOW.
